UNITED STATES PATENT OFFICE.

WILLIAM JAMES WHALEN, OF PITTSBURG, PENNSYLVANIA.

RIVETING-MACHINE.

SPECIFICATION forming part of Letters Patent No. 716,156, dated December 16, 1902.

Application filed January 28, 1902. Serial No. 91,551. (No model.)

To all whom it may concern:

Be it known that I, WILLIAM JAMES WHALEN, a citizen of the United States, residing at Pittsburgh, in the county of Allegheny and State of Pennsylvania, have invented a new and useful Improvement in Riveting-Machines, of which improvement the following is a specification.

This invention relates to new and useful improvements in portable riveting-machines.

The object of my invention is to provide a simple and practical apparatus of the above character adapted to be operated by hand and which can be manufactured and retailed at comparatively small cost.

In the accompanying drawings I have illustrated the apparatus in various ways, in which—

Figure 1 is a longitudinal side view of the apparatus complete. Fig. 2 is a longitudinal side view of the same in section. Fig. 3 is a plan view of the same in section along the line 3 3 of Fig. 2.

Referring to said drawings for a description of the detail parts of my invention and their operative arrangement, the numeral 1 designates a casing having the chamber 2 at one end and a block 3 secured within the other end, which block is provided with a handle 4. Loosely fitted into said chamber 2 is the header-die 5, having the concaved recess 5' in its face. This die is secured in operative position by a rod 6, which extends across the chamber through a longitudinal opening 6' in the rear portion thereof. A pair of reciprocating plungers 7 are fitted between the casing or chamber walls and a lug 8. These plungers are provided with heads 9 for alternate engagement with said die 5 and at their rear ends

40 with rounded shanks 10, which extend into openings 11 in said block 3. These plungers are forwardly actuated into engagement alternately with the die by springs 12, fitted to their shanked rear portions. To permit a forward movement of these plungers, so that they will come into engagement alternately and forcibly with the die, I provide a rotatable

shaft 14, having rigidly secured thereto the square cams 15 to engage with upward extensions 13 on said plungers. These cams are 50 set at an angle of forty-five degrees from one another, so that when they are revolved one plunger will be held in forcible position after the other has spent its force upon the die. To rotate said cams, I secure to the side of the 55 casing a gear-wheel 17 to mesh with a wheel 16 on the cam-shaft and provide the former with a hand-crank 18. The relative proportion between these wheels may be varied for increasing power and increasing or decreasing the rotation of the cams.

In practice the device is grasped in one hand by the handle 4. The die is then brought into engagement with the rivet, and by a rotary movement of the crank with the other 65 hand an alternate reciprocating movement is given to the plungers through the medium of the cams, which plungers, forcibly acting upon the die, will successfully head the rivet in a short time and with an expenditure of 70 little force upon the part of the operator.

Having thus fully shown and described my invention, what I claim as new, and desire to secure by Letters Patent, is—

In a device of the character described, a 75 casing having a movable header-die therein, reciprocating spring-pressed plungers adapted to engage said header-die, with shanks carried by said plungers, an apertured block carrying a handle and receiving said shanks 80 of the plungers, upward extensions carried by the plungers with a common shaft mounted in the casing and carrying cams for engagement with said extensions, and means for operating said shaft, substantially as described.

In testimony whereof I have hereunto signed my name in the presence of two subscribing witnesses.

WILLIAM JAMES WHALEN.

In presence of—

LOUIS MOESER,
M. HUNTER.
